RUBBER MAT

Arthur Bell, 12 Rogers Drive, Stoughton, Mass. 02072

Filed Aug. 3, 1972, Ser. No. 277,744

Term of patent 14 years

Int. Cl. D6—11

U.S. Cl. D6—209

FIG. 1

FIG. 1 is a top plan view of a rubber mat showing my new design;

FIG. 2 is an enlarged fragmentary top perspective view thereof;

FIG. 3 is a fragmentary bottom perspective view on a still larger scale;

FIG. 4 is a side elevational view on a very reduced scale; and

FIG. 5 is a cross sectional view taken on the line 5-5 of FIG. 2 on an enlarged scale.

I claim:

The ornamental design for a rubber mat, as shown and described.
